[57] CLAIM

The ornamental design for a rail element for a toy railway system, as shown and described.

DESCRIPTION

FIG. 1 is a top perspective view of a rail element for a toy railway system showing our new design;
FIG. 2 is a bottom perspective view thereof;
FIG. 3 is a front elevational view thereof, the side opposite being identical.

FIG. 4 is a side elevational view thereof, the side opposite being a mirror image,
FIG. 5 is a top plan view thereof; and,
FIG. 6 is a bottom plan view thereof.
